UNITED STATES PATENT OFFICE.

ALBERT N. FRIES, OF CINCINNATI, OHIO.

WINDOW-SHADE CATCH-PULLEY.

968,547.

Specification of Letters Patent. Patented Aug. 30, 1910.

Application filed January 24, 1910. Serial No. 539,302.

To all whom it may concern:

Be it known that I, ALBERT N. FRIES, a citizen of the United States, residing at Cincinnati, in the county of Hamilton and State of Ohio, have invented certain new and useful Improvements in Window-Shade Catch-Pulleys, of which the following is a specification.

My invention relates to improvements in window shade catch pulleys.

One of its objects is to provide improvements in the roller whereby the movements of the cord over the roller are more readily and perfectly controlled.

Another object is to provide improvements in the catch pulley frame where the cord enters and leaves said frame, to assist in guiding the cord in the desired direction.

It further consists in certain details of form, combination and arrangement, all of which will be more fully set forth in the description of the accompanying drawings in which:

Figure 1 is a front elevation of my improved catch pulley. Fig. 2 is a vertical section through the same on line $z-z$ of Fig. 1. Fig. 3 is a similar section on line $x-x$ of Fig. 1. Fig. 4 is a perspective view of the catch pulley frame from the rear.

In the accompanying drawings A represents the pulley or roller which has a deep central encircling groove a , and at opposite sides in pairs are more shallow grooves a' a'' , which diverge from the groove a in a spiral direction and gradually decrease in depth. The length of the grooves a' a'' being less than one-third of the circumference of the roller, there being preferably four grooves a' and four grooves a'' arranged equidistant apart on the circumference of the roller. The shallow portions of the grooves a' a'' are preferably provided with cross notches a^3 to assist in engaging and locking the cord. Opposite ends of the roller at a^4 are cylindrical.

B represents the frame or housing in which the pulley A is mounted or journaled upon an axle b . The housing B comprises two base or attachment plates b' b'' arranged at substantially right angles to each other and united at their meeting edges, each of said plates being provided with screw eyes b^3 b^4 by means of which either plate may be attached to the window frame or other support. The two plates b' b'' are further united by the webs or plates b^5 which support opposite ends of the roller axle b and serve to limit the end play of the roller. A slot D partly across the plates b' b'' in line with the central groove in the roller permits the cord to be led through either end of said slot to or from the roller, and is made use of where the cord h can not be employed as indicated in dotted line Fig. 2.

E E' represent lugs or projections from plate b' which are located on opposite sides of the central groove of the roller and extend to the plates b^5 , and serve as lateral guides to direct the cord into the central groove of the pulley. The plate b'' is provided with a projection F in line with the central groove of the pulley, and which serves as soon as the cord is slackened to deflect the slackened cord to one side of the central groove of the pulley to cause it to engage one or other of the side grooves a' a'' and thus to automatically wedge and lock the cord between the roller at one side of the central groove and plate b'' .

My improved catch pulley is adapted for general use wherever such a pulley is desired, and is further particularly designed for use where the shade roller is supported by a cord from the upper portion of the window frame by one catch pulley so that the shade roller may be raised and lowered as desired, and where the lower portion of the shade is adapted to be adjusted to and from the shade roller by means of a cord engaging a catch pulley attached to the lower portion of the window frame.

When so employed the catch pulley at the top of the window frame is attached so that the vertical section of the cord supporting the shade roller will enter between the lugs E E' and partly encircle the roller with the free end of the cord hanging down in front of the shade or preferably united to the free end of the cord from the lower end of the shade. By pulling on the free end of the cord the cord will be directed by lugs E E' into the central groove of the roller and will remain therein as long as a pull is exerted on the free end of the cord, which causes the cord to ride in the central groove of the pulley until the shade roller has been adjusted to the desired position, thereupon the pull on the free end of the cord is slackened, whereupon the slack cord engages the projection F, and is thereby diverted out of line with the central groove of the roller.

When so employed the catch pulley at the top of the window frame is attached so that the vertical section of the cord supporting the shade roller will enter between the lugs E E' and partly encircle the roller with the free end of the cord hanging down in front of the shade or preferably united to the free end of the cord from the lower end of the shade. By pulling on the free end of the cord the cord will be directed by lugs E E' into the central groove of the roller and will remain therein as long as a pull is exerted on the free end of the cord, which causes the cord to ride in the central groove of the pulley until the shade roller has been adjusted to the desired position, thereupon the pull on the free end of the cord is slackened, whereupon the slack cord engages the projection F, and is thereby diverted out of line with the central groove of the roller.

and caused to engage with one of the side grooves a' a^2 to lock the cord between the pulley and plate b^2 , which is almost instantaneously effected, and before the shade roller has acquired any momentum, even should the free end of the cord be entirely released by the operator. The lower catch pulley is set so that the vertical section of cord from the lower end of the shade will enter between the lugs E E' , and is operated in the manner above described. The deep central groove of the roller prevents wear on the cord, and facilitates retaining the cord in said groove when both ends of the cord are under strain, to secure the desired adjustment in either direction, while the short diverging grooves arranged in pairs facilitate and insure the positive catching and locking of the cord as soon as the cord is slackened, and before momentum has been acquired, whether the slackened cord moves to the right or left of the central groove.

My improved supporting frame may be advantageously employed with pulleys of the form heretofore in use, but attains superior results when used with pulleys such as shown herein.

The mechanism herein illustrated and described is capable of considerable modification without departing from the principle of my invention.

Having described my invention, what I claim is:

1. In a mechanism of the character described, a pulley having a central groove and diverging and diminishing grooves leading therefrom at opposite sides, and a supporting frame on which said pulley is pivotally mounted, said frame comprising two plates arranged at substantially right angles and

united at their meeting edges, with brackets carrying the pulley journals, projecting lugs carried by one of said plates to guide a cord into the central groove of said pulley, and a projection carried by the other plate adapted to divert the cord when slack from said central groove into one of the diverging grooves. 45

2. In a mechanism of the character described, a pulley having a central groove and short diminishing grooves diverging in pairs from opposite sides of said central groove, and a supporting frame on which said pulley is pivotally mounted, said frame having lugs at one edge to direct a cord into the central groove of said pulley, and a projection near the opposite edge adapted to divert the cord when slack from said central groove into a diverging groove. 50 55

3. In a mechanism of the character described, a pulley having a central groove and short diminishing grooves, diverging in pairs from opposite sides of said central groove, and a supporting frame comprising two plates arranged at right angles and 60 65 united at their meeting edges, said plates carrying supports for the pulley journal, lugs carried by one of said plates to guide a cord into the central groove of said pulley, and a projection carried by the other plate adapted to divert the cord when slack from said central groove into one of the diverging grooves. 70

In testimony whereof I have affixed my signature in presence of two witnesses.

ALBERT N. FRIES.
